BY George L. C. *ATTORNEY.*

UNITED STATES PATENT OFFICE.

LOUIS WOJIDKOW, OF BROOKLYN, NEW YORK.

DESIGN FOR A KETTLE.

SPECIFICATION forming part of Design No. 25,478, dated May 12, 1896.

Application filed April 11, 1896. Serial No. 587,223. Term of patent 3½ years.

To all whom it may concern:

Be it known that I, LOUIS WOJIDKOW, a citizen of the United States, residing at Brooklyn, in the county of Kings and State of New York, 5 have invented and produced a new and original Design for Kettles, of which the following is a specification, reference being had to the accompanying drawing, which shows a view of the same in side elevation.

10 The leading feature of my design consists of a body having an unusually small restricted bottle-like neck, said body decreasing in width toward the bottom and formed with a long narrow spout and a fanciful handle.

A represents the body of the kettle having 15 the peculiar outlines, as shown, and formed with the narrow restricted neck B, covered with a cap C having somewhat the shape of an acorn. From the body A extends the long curved spout D and fanciful bracket E, and 20 from the opposite side the fanciful handle F.

What I claim is—

The design for a kettle substantially as herein shown and described.

LOUIS WOJIDKOW.
